UNITED STATES PATENT OFFICE.

CHARLES HAAS, OF STRASSBURG, GERMANY, ASSIGNOR TO THE FIRM OF HERREN-SCHMIDT & CO., OF STRASSBURG, GERMANY.

ELECTRIC REVERSING-SWITCH AND CIRCUIT-CLOSER.

1,074,860.

Specification of Letters Patent.

Patented Oct. 7, 1913.

Original application filed September 19, 1912, Serial No. 721,152. Divided and this application filed January 30, 1913. Serial No. 745,071.

To all whom it may concern:

Be it known that I, CHARLES HAAS, a citizen of the Empire of Germany, and residing at Strassburg, Alsace, in the Empire of Germany, have invented certain new and useful Improvements in Electric Reversing-Switches and Circuit-Closers, of which the following is a specification.

My novel electric reversing switch, although capable of a general application is intended especially for use in connection with electric plants for periodically and automatically reversing working machines, for instance tanning drums and the like, and my improvements in such switches relate to certain novel combinations and arrangements of parts, as are fully described hereinafter.

The present application is a division of my copending application for Letters Patent, Serial Number 721,152, filed September 19, 1912.

In order to make my invention more clear, I refer to the accompanying drawing, in which similar letters denote similar parts throughout the several views, and in which:

Figure 1 is an elevation, partly in section, of one form of execution of a switch constructed according to my invention, and Fig. 2 is a plan of the mercury cups employed in this form of construction, together with some adjacent parts.

In these figures two parallel sets of three mercury cups 1, 2, 3 and 4, 5, 6 in each set are disposed on a suitable insulating base 7. The two outer mercury cups 1 and 3 or 4 and 6 of each set are preferably curved to a common arc and the bottom of each middle mercury cup 2 or 5 is preferably curved to an arc of a smaller radius having the same center. A shaft 8 is mounted above the two middle mercury cups 2, 5 to turn in suitable bearings 9 and 10, which bearings are only indicated in Fig. 2, as they may be varied to suit the circumstances. On the shaft 8 are fastened and insulated therefrom two parallel switches 11 and 12, each of which consists of a disk permanently dipping in the mercury of the middle cup 2 or 5, and an arm carrying two opposite dippers. One dipper of each switch 11, 12 is adapted to dip in one outer cup 1, 4 as shown and the other dipper to dip in the other outer cup

3, 6. One outer cup 1 of the one set is connected by a conductor 13 with the opposite cup 6 in the other set and the outer cup 4 of the other set is connected by a conductor 14 with the opposite cup 3 of the first set.

In Figs. 1 and 2 it is assumed, that the automatic reversing device be alone contained in an electric three-phase plant for driving a single working machine by means of an electromotor. Then two phase leads a^1, a^2 coming from the source are connected with two left outer mercury cups 4, 1 and the third phase line a^3 is connected by its continuation b^3 with the electromotor, while the latter is connected by two phase leads b^1, b^2 with the two middle mercury cups 2 and 5 as shown in Fig. 2. Fastened on the shaft 8 is a pinion 15, which meshes with a toothed segment 16 rocking at 17 in some frame or frame part (not shown.) The segment 16 has a rear arm 18 and a horizontal arm 19. A fly wheel 21 turning around 22 in Fig. 1 is in any known manner constantly and slowly driven in one direction only. For example the fly wheel 21 may be fastened on a shaft 22, which is driven from some electromotor (not shown) by means of a gearing 23, 24 . . . (indicated by dotted circles). The fly wheel 21 is shown to be stepped on the periphery, so that the right half has a larger radius than the left half and two opposite portions between the halves have a radius of a length between the two radii. The rear arm 18 of the segment 16 is adapted to bear against the periphery of the fly wheel 21 under the pressure of a weight 20 at the free end of the horizontal arm 19. The ratio of the two-armed lever 16, 18 is such, that one dipper of the two switches 11, 12 fully engages in the respective left mercury cup 1, 4, when the upper arm 18 bears against the left half of the fly wheel 21 having the smallest radius, and the other dipper dips in the respective right mercury cup 3, 5, when the arm 18 bears against the wheel portion having the largest radius. When the arm 18 bears against either portion having the middle radius, the segment 16 is to occupy the middle position, so that neither dipper of the two switches 11, 12 dips in any cup. When the dippers of the two switches 11, 12 dip in the two left mercury cups 1, 4 as shown, the latter are

thereby electrically connected with the middle mercury cups 2, 5 and consequently the source is connected by a^1 , a^2 , a^3 with the working electromotor by b^1 , b^2 , b^3 , which 5 motor will then run in one direction. When the other dippers dip in the two right mercury cups 3, 6, the electromotor will run in the opposite direction.

This device is useful for automatically reversing working machines which require to 10 run for a period in one direction and for another period in the other direction. For example tanning drums belong to this class of working machines.

15 Having now described my invention, what I desire to secure by a patent of the United States is:

1. In an automatic reversing device, the combination with two parallel sets of three 20 contacts each, of a rocking shaft above the two middle contacts, two switches fastened on and insulated from said shaft and constantly electrically connected with the two middle contacts and adapted to simultaneously come in contact either with two outer 25 contacts on one side of said shaft or with the two outer contacts on the other side, conductors connecting the outer contacts on both sides alternately with those on the other side in the two sets, a fly wheel 30 stepped on the periphery, means for constantly driving said fly wheel in one direction, a pinion on said rocking shaft, a two-armed lever having a long arm and a short

arm, a toothed segment on the long arm of 35 said lever for meshing with said pinion, the short arm of said lever being adapted to bear against the periphery of said fly wheel, and means for pressing the short arm of 40 said lever against said fly wheel.

2. In an automatic reversing device, the combination with two parallel sets of three mercury cups each, of a rocking shaft above the two middle mercury cups, two switches fastened on and insulated from said shaft, 45 said two switches constantly dipping in the two middle mercury cups and adapted to simultaneously dip either in the two outer mercury cups on one side of said shaft or in the two outer mercury cups on the other 50 side, conductors for connecting the outer contacts on both sides alternately with those on the other side in the two sets, a fly wheel stepped on the periphery, means for constantly driving said fly wheel in one direction, a pinion on said rocking shaft, a two-armed lever having a long arm and a short arm, a toothed segment on the long arm of 55 said lever for meshing with said pinion, the short arm of said lever being adapted to bear against the periphery of said fly wheel, and means for pressing the short arm of 60 said lever against said fly wheel.

CHARLES HAAS.
